DESIGN FOR A COMBINED STEERING WHEEL AND HORN RING

Irving R. Cheris, Chicago, Ill.

Application April 11, 1938, Serial No. 76,420

Term of patent 3½ years

To all whom it may concern:

Be it known that I, Irving R. Cheris, a citizen of the United States, residing at Chicago, in the county of Cook and State of Illinois, have invented a new, original, and ornamental Design for a Combined Steering Wheel and Horn Ring, of which the following is a specification, reference being had to the accompanying drawing forming part thereof, in which the single figure

is a perspective view of my combined steering wheel and horn ring showing my new design.

The dominant features of my design reside in the horn ring spoke members.

I claim:

The ornamental design for a combined steering wheel and horn ring, as shown and described.

IRVING R. CHERIS.
